PIPE FITTING

John Fabian Brindley Jackson, Charlwood, and Donald Colbridge, Crawley, England, assignors to A.P.V.-Paramount Limited, Crawley, England

Application March 31, 1958, Serial No. 50,232

Claims priority, application Great Britain
October 1, 1957

Term of patent 14 years

(Cl. D91—3)

Figure 1 is a top perspective view of a pipe fitting showing our new design;

Figure 2 is a perspective view thereof taken from the bottom and opposite side;

Figure 3 is a side elevational view thereof; and

Figure 4 is an elevational view of the pipe fitting as seen from one end thereof.

We claim:

The ornamental design for a pipe fitting, as shown.
